US00D986270S

(12) **United States Design Patent** (10) **Patent No.:** **US D986,270 S**
(45) **Date of Patent:** **** May 16, 2023**

(54) **DISPLAY SCREEN WITH GRAPHICAL USER INTERFACE**

(71) Applicant: **Spotify AB**, Stockholm (SE)

(72) Inventors: **Karl Humphreys**, London (GB);
Aaron Paul Harmon, New York, NY
(US); **Nicola Felaco**, Stockholm (SE)

(73) Assignee: **Spotify AB**, Stockholm (SE)

(**) Term: **15 Years**

(21) Appl. No.: **29/868,401**

(22) Filed: **Dec. 1, 2022**

(57) **CLAIM**

The ornamental design for a display screen with graphical user interface, as shown and described.

DESCRIPTION

The FIGURE is a front view of a display screen with graphical user interface showing our new design.

The peripheral dash-dot-dash broken lines illustrate a display screen or portion thereof and form no part of the claimed design.

1 Claim, 1 Drawing Sheet
